UNITED STATES PATENT OFFICE.

WILLIAM B. POTTER AND EDWARD M. HEWLETT, OF SCHENECTADY, NEW YORK, ASSIGNORS TO GENERAL ELECTRIC COMPANY, A CORPORATION OF NEW YORK.

END-PLAY DEVICE FOR ROTARY MACHINES.

SPECIFICATION forming part of Letters Patent No. 712,590, dated November 4, 1902.

Application filed March 27, 1901. Serial No. 53,045. (No model.)

To all whom it may concern:

Be it known that we, WILLIAM B. POTTER and EDWARD M. HEWLETT, citizens of the United States, and residents of Schenectady, county of Schenectady, State of New York, have invented certain new and useful Improvements in End-Play Devices for Rotary Machines, (Case No. 1,565,) of which the following is a specification.

10 This invention relates to devices for maintaining end play of the shafts of rotary machines, and is especially useful in connection with certain types of electric generators and motors. In such machines difficulty has been 15 found from grooving of the commutator by the brushes, which bear upon the same portion of the commutator-surface continuously and tend to form grooves or tracks. In types of machines driven by belts no such difficulty 20 is experienced, as an end play of the shaft is maintained which prevents the grooving, but in other types of machines not belt-connected—such as rotary converters, motor-generators, and others where the rotary element is 25 free to obey its own tendency to shift in its bearings—the field-magnet holds the armature in a certain definite position and will groove the commutator under the brush-tread unless special provisions are adopted to prevent it. Various devices have been suggested 30 to avoid this trouble, all of them having provisions for positively maintaining a to-and-fro relative movement of the brushes and shaft, so as to distribute the brush-tread over the 35 surface of the commutator. Our invention relates to the type of such devices covered by a patent issued to Henry Geisenhoner, No. 669,630, dated March 12, 1901, in which the shaft is given an end thrust by an inclined 40 disk, in the face of which is mounted a steel ball adapted to roll in a circular groove around the face of the disk. In the construction shown in this patent when the shaft is drawn back to the normal position in which 45 it would be maintained by the field-magnet of the machine it forms a contact with the ball, rolling the latter around in the circular groove and by reason of the inclination of the disk giving the shaft a forward thrust 50 against the bias of the field-magnet. This

organization is very effective in practice, but maintains a more rapid movement of the shaft than is desirable, and it is the object of our invention to slow down the number of oscillations of the shaft. We effect this result by substituting for the ball a roller which bears against the end of the shaft a short distance from its axial center, the shaft of the roller, with which it is rigid, rolling on a surface having a small inclination relatively 55 to the end of the shaft. By this means a considerable number of revolutions of the machine-shaft must occur before the forward thrust is completed, and the reciprocating movement is therefore much slower than in 60 the device above referred to.

Our invention therefore comprises means for effecting end play of a shaft comprising a thrust-surface inclined to the axis of the shaft, means adapted to engage said surface 70 and the shaft when the latter drifts to its normal position, and reduction-gearing between the two to insure a slow outward thrust to the shaft.

It comprises also other features the novelty 75 of which will be hereinafter described, and indicated in the claims.

In the accompanying drawings, which illustrate the invention, Figure 1 represents the shaft of a machine, such as a rotary converter; 80 and Fig. 2 is a sectional detail thereof.

The shaft is shown in Fig. 1 as at the limit of its outward motion in its bearing 2 under the influence of the end-play device and against the bias given it by the magnetic field 85 in which the armature which the shaft carries rotates. The relation of the armature and its field at the limits of end play is shown in Fig. 2, the full lines indicating the abnormal position to which the armature is shifted 90 by the end-play device. Opposite the end of the shaft is mounted a box 3, provided with ways on its inner surface, along which slides a disk 4, pressed by a four-arm leaf-spring 5, riveted to a set-screw 6, which is adjustable 95 in the end of the box 3. The disk 4 has at the end which faces the shaft an inclined edge 7, the top edge of which is nearer the shaft than the bottom edge. In the disk is mounted a threaded plug 8, through which passes freely 100

a spindle 9, mounted in the plug by ball-bearings, as indicated. The disk 4 is split at one side, and a bolt passing through the two jaws, as indicated at 10, permits the plug 8 to be 5 clamped in any position in which it is adjusted. Rigidly connected with the spindle 9 is a projection 11, forming a bearing for the roller 12, provided with an adjusting-nut and jam-nut, as 13 13°, for locking it in a position of adjustment to permit easy rotation. Forming part of the roller 12 is a cylindrical extension 14, bearing on inclined edge 7. A steel shoe 15 is screwed to the end of the shaft at a point close to its axial center. As shown 15 in Fig. 1, the shaft is in the act of being shifted against the bias given by the magnetic field. A moment later it will have been thrown to the left, clearing contact with the roller 12, thereby permitting the latter to drop 20 by gravity to a diametrically opposite position to that indicated in the drawings. The shaft will then drift to the right under the bias afforded by the magnetic field until the shoe 15 is brought up against the roller 12, 25 which will then have dropped by gravity to the position indicated by dotted lines. The shaft will then grip the roller and cause it to rotate, its rate of travel depending upon the relative diameters of the roller and the distance 30 from the center of the shaft to its point of engagement therewith, and its rate of travel on the inclined edge 7 of the disk will depend on the relative diameters of the bearing edge of said disk to the extension 14. This 35 organization forms, in fact, a sun-and-planet gearing, in which a slow thrust is communicated to the rotary element compared to the speed of revolution of its shaft. Thus a comparatively slow forward thrust will be effected. 40 During the time when the roller is traveling over the edge of the disk 4 the spring 5 is being put under tension and assists the roller in giving an outward thrust to the shaft.

What we claim as new, and desire to secure 45 by Letters Patent of the United States, is—

1. Means for effecting end play in rotary machines, comprising an inclined thrust-surface mounted in a plane transverse to the shaft, a roller on said surface operated by the shaft at one limit of its end play, and speed-reducing gearing between the shaft and thrust-surface.
2. Means for effecting end play in rotary machines, comprising an inclined thrust-surface 55 mounted in a plane transverse to the

shaft, a roller mounted to travel a circular path on said surface, and a roller of different diameter rigidly connected thereto adapted to be operated by the shaft at one limit of its end play.

60

3. Means for effecting end play in rotary machines, comprising a shaft having a normal bias to shift in one direction, an inclined surface opposite the end of the shaft, a roller adapted to traverse a circular path on the 65 surface, and a roller of larger diameter rigidly connected therewith adapted to engage the shaft at a point eccentric to its axis at or near the end of its normal thrust, the roller being adapted to shift to the remote end of 70 the incline when disengaged from the shaft.

4. Means for effecting end play in rotary machines, comprising a shaft having a normal bias to shift in one direction, an inclined thrust-surface opposite the end of the shaft, a 75 spindle journaled centrally in the thrust-surface, and a roller carried by the spindle revolving in a plane transverse to the same having two bearing-surfaces of different diameter, one engaging the thrust-surface and 80 the other gripped by the shaft when shifted under its bias.

5. Means for effecting end play in rotary machines, comprising a shaft having a bias 85 in one direction, an inclined surface mounted in a plane transverse to the shaft, sun-and-planet gearing operated by the shaft when shifted under the bias, and a roller driven over the inclined surface by said gearing.

6. Means for effecting end play in rotary 90 machines, comprising a shaft having a bias in one direction, an inclined surface mounted in a plane transverse to the shaft, and means for effecting a thrust to the shaft against its bias continuing during more than a single 95 revolution of said shaft.

7. Means for regulating end play in rotary machines, comprising a shaft, means for effecting end thrust, and means for maintaining a slow speed of movement during said 100 end thrust compared with the speed of the shaft.

In witness whereof we have hereunto set our hands this 25th day of March, 1901.

WILLIAM B. POTTER.
EDWARD M. HEWLETT.
